DESCRIPTION

FIG. 1 is a front perspective view of one embodiment of a lighting controller cover;
 FIG. 2 is a back perspective view of the lighting controller cover of FIG. 1;
 FIG. 3 is a front view of the lighting controller cover of FIG. 1;
 FIG. 4 is a back view of the lighting controller cover of FIG. 1;

FIG. 5 is a side view of the lighting controller cover of FIG. 1;
 FIG. 6 is an opposing side view of the lighting controller cover of FIG. 1;
 FIG. 7 is an end view of the lighting controller cover of FIG. 1;
 FIG. 8 is an opposing end view of the lighting controller cover of FIG. 1;
 FIG. 9 is a front perspective view showing another embodiment of a lighting controller cover;
 FIG. 10 is a back perspective view of the lighting controller cover of FIG. 9;
 FIG. 11 is a front view of the lighting controller cover of FIG. 9;
 FIG. 12 is a back view of the lighting controller cover of FIG. 9;
 FIG. 13 is a side view of the lighting controller cover of FIG. 9;
 FIG. 14 is an opposing side view of the lighting controller cover of FIG. 9;
 FIG. 15 is an end view of the lighting controller cover of FIG. 9;
 FIG. 16 is an opposing end view of the lighting controller cover of FIG. 9;
 FIG. 17 is a front perspective view showing yet another embodiment of a lighting controller cover;
 FIG. 18 is a back perspective view of the lighting controller cover of FIG. 17;
 FIG. 19 is a front view of the lighting controller cover of FIG. 17;
 FIG. 20 is a back view of the lighting controller cover of FIG. 17;
 FIG. 21 is a side view of the lighting controller cover of FIG. 17;
 FIG. 22 is an opposing side view of the lighting controller cover of FIG. 17;
 FIG. 23 is an end view of the lighting controller cover of FIG. 17;
 FIG. 24 is an opposing end view of the lighting controller cover of FIG. 17;
 FIG. 25 is a front perspective view showing still another embodiment of a lighting controller cover;
 FIG. 26 is a back perspective view of the lighting controller cover of FIG. 25;
